UNITED STATES PATENT OFFICE.

ALBERT W. MARTIN AND JACOB N. MARTIN, OF INDIANAPOLIS, INDIANA.

MULTIPLE-JOINT-GRINDING MACHINE.

Application filed July 6, 1925. Serial No. 41,757.

The object of this invention is an improvement in the multiple grinding of joints or the ends of pipes or like articles. The invention consists in mounting a plurality of grinding laps and spindles in a frame movable into position over a multiplicity of joints or pipes for grinding the same, and means for simultaneously giving the laps both rotary and gyratory movement, whereby the grinding will be facilitated and smooth joints or surfaces will be produced because of the cross grinding due to the gyratory movement of the laps in addition to the rotary movement. Said means is such as to rotate the individual laps and spindles and at the same time move the frame, in which the spindles are mounted by universal joints, in circular paths so as to give the desired gyratory movement to the laps and spindles. Also the spindles are mounted in the frame carrying the same so that they have oscillatory movement, each spindle being mounted in a ball which furnishes a substantially universal bearing and at the same time has means for rotating the same when in any position. To the foregoing end the frame in which the lap spindles are mounted has a horizontal circular swinging movement over a stationary plate or frame which is fixed in relation to the joints or pipes to be ground and this horizontal circular swinging movement of the frame carrying said spindles is effected by the same means which rotates the individual spindles.

The invention is not, however, limited to grinding pipe joints or employing multiple grinding elements although the invention was made for the purpose of grinding pipe joints.

The full nature of the invention will be understood from the accompanying drawings and the following description and claims:

In the drawings, Figure 1 is a perspective view of the machine before the carrier containing the grinders has been moved up into operative position over the pipes, parts of the device being omitted. Fig. 2 is a similar view of the apparatus after the carrier of the grinders has been moved up into operative position and showing the machine in operation, part of the device being omitted. Fig. 3 is a plan view of the grinder head or carrier. Fig. 4 is a vertical

central section on the line 4-4 of Fig. 3. Fig. 5 is a section on the line 5-5 of Fig. 3, showing one grinder in its mounting, the rest being broken away, and showing the grinder in its idle and vertical position. Fig. 6 is the same as Fig. 5, showing the position of the grinder in operation and gyratory positions of the grinder being indicated by dotted lines. Fig. 7 is a reproduction of the right-hand end of Fig. 4, on a larger scale. Fig. 8 is the same as Fig. 7 with the parts in altered position. Fig. 9 is a section on the line 9-9 of Fig. 7. Fig. 10 is a section on the line 10-10 of Fig. 6. Fig. 11 is a section on the line 11-11 of Fig. 6. Fig. 12 is a central vertical section of a modified form of lap spindle and its mounting, with the spindle in its idle position. Fig. 13 is the same with the spindle in operative position, and different positions of the spindle and lap being shown by dotted lines. Fig. 14 is a diagram showing in plan the gyratory movement of the grinding element, the lap and spindle. Fig. 15 is a vertical cross section on the line 15-15 of Fig. 1.

A plurality of steam pipes 15 is shown in Fig. 1, mounted in a clamp 16. The machine shown herein is adapted to grind simultaneously the ends of a large number of steam pipes which are arranged together in cross rows and substantially equidistant from each other. Means not shown hold the group of steam pipes in place while being ground.

The means for grinding the ends of the steam pipes are mounted on a carriage 17 in the form of a plate supported by end frames 18 carried by wheels or rollers 19 that travel on tracks or guideways 200, as shown in Fig. 1, whereby the mechanism is moved over the group of steam pipes for grinding the same and moved away therefrom after they are ground. The plate 17 is cut out at 18, see Fig. 3, so as to form two longitudinal and parallel openings therethrough so that it is in the nature of a frame plate and the spindle carrying frame is supported thereon, as shown in Fig. 4, and so as to have a gyratory movement, as hereafter explained.

The spindle frame consists of a bottom plate 20, a parallel top plate 21, and intermediate side plates 22, as shown in Figs. 4 and 5. The lap spindles are mounted on the lateral portions of said frame, as shown

in Fig. 3, by the means shown in Figs. 5 and 6. Bushings 23 are secured in round holes or openings in the plates 20 and 21, which register with each other, as shown in Fig. 5, in which the hub 24 of a spur gear 25 is mounted. There are two members to each hub 24, an upper member and a lower member that have flat sides which meet each other and the spur gear 25 is a ring secured tightly on said abutting hub members so that when assembled they are a fixed unit. The two hub members 24 are centrally and circularly bored out to form a seat for a bearing ball 26 in which the lap spindle device is mounted vertically as shown. This arrangement is to enable the lap to be given a gyratory movement, substantially as shown in Figs. 2 and 6. Pins 27 extend radially from opposite sides of the bearing ball 26 into vertical recesses 28 in the hub members 24 of the gear 25 to enable the lap to be oscillated as shown in Fig. 6. With this oscillatory movement the ball 26 oscillates on two horizontal axes and the walls of the slots 28 limit said oscillatory movement of the grinders. One of these axes is through the pins 27 and the other is at right angle to the axis through the pins 27. The width of the slots 28, as seen in Fig. 11, is only slightly greater than the pins 27. Consequently the ball 26 does not turn on a vertical axis independently of the gear 25. Therefore, the turning movement of the grinders is effected by the gear 25 which carries the ball 26 with it, but during such turning movement, the ball and grinders may rock, as shown in Fig. 6, on a horizontal axis to a limited extent.

The gears 25 of the various grinders are rotated in the direction of the arrows in Fig. 3 simultaneously by power coming from a motor 30, see Fig. 1, through a motor shaft 31, see Figs. 3 and 4, and gear 32 mounted on a sleeve 33 carried by said motor shaft and lying between the plates 20 and 21 in position to mesh with the two gears 25 on opposite sides of the gear 32, as shown in Fig. 3. As seen there are two series of gears 25 and they are in mesh with each other in succession so that all of them in each series are driven by the gear 25 which meshes with the driving gear 32. This causes all of the grinders in the machine to be simultaneously actuated. The motor is mounted on a rod 35 carried in slots 36 in the upper ends of uprights 37 secured to and extending from the grinder carrying frame, as seen in Fig. 1. The shaft 31 has a collar 38 thereon which rides upon the bushing 33 and which aids in holding it in position, although said parts 31, 33 and 32 are secured rigidly together in order that the shaft may impart power constantly to the gear 32 and thereby the grinder driving wheels 35 are all constantly operated.

The grinder and its mounting is shown in

Figs. 5 and 6. It consists of a grinder head 40, having a round central socket at 41 on the underside thereof in which a shank 42 of a lead lap grinder 43 is secured by a screw or bolt 44. The head 40 has extending up centrally from it a spindle 45, the upper end of which projects partially through a tube 46 and is supported therein by a disk 47 secured on the stem by a screw 48 and resting on a shoulder 49 in the tube 46 made by boring out the upper end of the tube to form the enlarged port 50. This renders the screw 48 accessible for assembling and disassembling the parts. The grinder is held in its upper and idle position in the frame formed of the plates 20 and 21 by a latch plate 51 which is pivoted on the plate 21 by a screw 52 and has a notch at 53 in the side thereof for engaging the squared plate 54 of the sleeve 46, as seen in Fig. 5. The latch 51 has a finger piece 55, as shown, whereby it can be moved into the holding position shown in Fig. 6.

When the group of spindles and the carriage supporting the same are moved from the position shown in Fig. 1, to the position shown in Fig. 2, over the ends of the steam pipes to be ground, the grinders are dropped and moved into the grinding position shown in Fig. 6, so that the laps 43 will engage the upper ends of the pipes 15, as seen in Fig. 2. This is done by releasing the latches 51 by hand, throwing them into the position shown in Fig. 6. Then the grinder spindles 41 will move down by gravity, or can be moved down by hand, from the position shown in Fig. 5 to that shown in Fig. 6. The central opening 56 in the ball 26, is rectangular, as shown in Fig. 10, so that when the ball 26 and the squared lower plate 54 of the sleeve 46 are in corresponding positions, as shown in Fig. 1, it will pass down through the ball 26, and it is pressed down below the same by hand and then the sleeve 46 is turned forty-five degrees, whereupon the spring 57 will push the squared part 54 up into the squared recess 58 in the bottom of the ball 26, to be seen in Fig. 5, and also shown in Fig. 10. The notches 58 are small triangular notches at each side of the opening 56, as seen in Fig. 10. When the squared end 54 of the sleeve 46 thus fits into the notches 58, it is obvious that the rotation of the gear 25 and ball 26 will cause the rotation of the grinder. The spring 57 is a spiral spring surrounding the spindle 45 and at its lower end bears against the head 40 and in a tubular seat 59, and at its upper end bears against a collar 60 secured on the reduced lower end of sleeve 46 below and spaced from the squared plate 54 on the sleeve 46 so as to permit the lap 51 to be moved into the position shown in Fig. 6.

The members 24 of the hub of the gear 25, as shown in Figs. 5 and 6, are cut away cen-

trally and conically on the upper side and on the under side, as shown, to permit the oscillatory movements of the grinder spindle which, as stated, can oscillate in two directions on the horizontal axis of the ball 26.

The rotation of the grinding laps 43 is caused by the gearing heretofore explained which constantly rotates the gears 25. The means for causing the gyratory movement 10 of the grinders will now be explained. As shown in Figs. 3 and 4, the middle portion of the plate 17 is recessed at 65 in two places near the ends to receive a wrist pin 66 eccentrically secured to an internal gear 67 15 rotatably mounted on the lower end of a hub 68 of a gear 69 and concentric therewith. The upper end of the hub 68 is mounted in the plate 21. The gear 69 lies between the plates 20 and 21, and meshes with gears 25 20 on each side thereof, as seen in Fig. 3, so as to be driven thereby. A fixed gear 70 is eccentrically mounted on the hub 68 of the gear 69, as shown in Figs. 7 and 8, and meshes with the internal gear 67. The gear 25 25 70 is held stationary by a plate 71 which is provided with a flat sided opening 72 in it, as seen in Fig. 9, so that said plate fits astride the flattened hub 73 of the gear 70, and the end of the plate 71 is held in place 30 by a screw 74 passing through the plate 20. This arrangement enables said parts to be assembled and disassembled readily.

From the foregoing explanation it will be seen that gear 69 rotates on the stub shaft 35 which has an eccentric arranged to give a bodily rotative movement to gear 70, which being held against rotation about its own axis, and being in mesh with internal gear 67, causes said last-mentioned gear to rotate 40 about the axis 68. The eccentric 66 on gear 67 rotates about the axis 68, also giving relative circular bodily movement of the spindle frame 20—21 relative to the carriage 17. The carriage being the immovable member, a circular bodily movement is transmitted 45 to the spindle frame. Each spindle, therefore, has a gyratory movement as shown in full lines, and various other positions by dotted lines, in Fig. 14. This gives 50 to the frame carrying the grinders, as a whole, a constantly changing gyratory movement, as indicated in Fig. 2, which causes a constant rotation of the vertical plane of the angle between the grinder spindles and the axes of the pipes 55 being ground about said axes. This causes constant cross grinding of the ends of the pipes and a uniform grinding of all parts thereof and prevents striae or rings and thus smoothly grinds the ends of the pipes. During 60 this movement the grinding laps are all held yieldingly in engagement with the ends of the pipes by the springs 57. When the process is finished, the laps are all lifted and latched in position, as shown in Fig. 5, and

the mechanism rolled out of the way from over the ends of the pipes.

The lap 43 is preferably formed as shown in Fig. 5, with a circular chamber 80 in the upper portion thereof surrounding the head 70 40 for holding abrading material such as fine emery in solution, and said chamber 80 communicates with the inner grinding surface of the lap through small passages 81, whereby the lap is conveniently supplied 75 with abrading material.

A modified form of spindle construction is illustrated in Figs. 12 and 13, which is somewhat simpler than that shown in Figs. 5 and 6. The latch plate 51, shown in Fig. 80 5, is omitted and in its place there is a loose plate 85 resting upon the frame plate 21. The tube 46 of the spindle extends through the plate 85 loosely and through a loose sleeve 86 which rests loosely upon the plate 85. The sleeve 86 extends for about half the distance of the tube 46 and at its upper end is notched at 87 to receive pins 88 which extend laterally from opposite sides of the tube 46 and thereby the latch and spindle and tube 90 46 are held in their upper and idle position, that is, in the same position as in Fig. 5. The sleeve 86 is vertically slotted at 89 on opposite sides from the top almost to the bottom, and by turning the sleeve 86 or the tube 46, the pins 88 are brought into registry with the slots 89 and that will permit the spindle and lap to be moved downward to the operating position, as shown in Fig. 13, the same as in Fig. 6. Otherwise the mechanism in the modified form shown in Figs. 12 and 13 is the same as that shown in the other figures excepting that the collar 60 shown in Fig. 6 is omitted in the form shown in Figs. 12 and 13, and the spring 57 at its 100 upper end bears directly against the square collar 54. The hole in plate 85 is large enough to permit the oscillation and gyratory movement of the spindle.

By "gyratory" herein is meant the movement of the spindle in a direction around the periphery of a cone with the apex down inasmuch as the pipe joint or other article being ground remains fixed during the grinding and the lap on the lower end of the spindle 105 is held from lateral movement thereby while the upper end of the spindle is given a circular swinging movement by a circular bodily movement of the spindle frame 20—21.

The invention claimed is:

1. A multiple joint grinding machine for simultaneously grinding the ends of a plurality of pipes rigidly mounted in a stationary work holder including a grinding lap and spindle for each of said pipes, a carriage movable into and out of position over said pipes, a frame carried by the carriage in which the grinder spindles are each mounted by a universal joint, and means for simultaneously rotating the grinder spindles and 125 130

giving the frame a circular movement relative to the carriage whereby said lap and spindle will be given simultaneous gyratory and rotary movements, substantially as set forth.

2. A multiple joint grinding machine, as set forth in claim 1, with a single power supplying means mounted on the carriage for both rotating the grinder spindles and giving the frame a circular movement relative to the carriage whereby each lap and spindle will be given simultaneous gyratory and rotary movements.

3. A multiple joint grinding machine for simultaneously grinding the ends of a plurality of pipes rigidly mounted in a stationary work holder, including a grinding lap and spindle for each of said pipes, a carriage movable into and out of position over the pipes, a frame in which the grinder spindles are each mounted by a universal joint, means carried by the frame for rotating all the spindles, rotary means carried by the frame, means driven by said rotary means having an eccentric portion engaging the carriage, whereby the frame is given a circular movement relative to the carriage, and

each lap and spindle is given simultaneous rotary and gyratory movements.

4. A multiple joint grinding machine, as set forth in claim 3, with means driven by the means which rotates the grinders for operating the means carrying the eccentric portion for causing the circular movement of the frame simultaneously with the rotary movement of the grinders.

5. A multiple joint grinding machine, as set forth in claim 3, said frame having a plurality of bearings with gears mounted therein, one for each grinder spindle and said gears meshing with each other, a ball loosely mounted in the center of each gear for centrally carrying one of the grinder spindles, and means for yieldingly forcing each grinder into engagement with the end of the pipe being ground while the machine is in use, whereby the grinders will operate constantly during the gyratory movement of the frame carrying the same.

In witness whereof, we have hereunto affixed our signatures.

ALBERT WM. MARTIN.
JACOB N. MARTIN.
